UNITED STATES PATENT OFFICE.

CHARLES M. OHLSEN, OF CHICAGO, ILLINOIS.

DOOR-FASTENING.

1,264,967.

Specification of Letters Patent.

Patented May 7, 1918.

Application filed September 22, 1917. Serial No. 192,643.

To all whom it may concern:

Be it known that I, CHARLES M. OHLSEN, a citizen of the United States, residing at Chicago, in the county of Cook and State 5 of Illinois, have invented certain new and useful Improvements in Door-Fastenings, of which the following is a specification.

My invention relates to door fastenings and has for its primary object the provision 10 of an improved device of this character by means of which a door, normally held fastened in closed position by a spring so stiff that an ordinary person, unaided, cannot bend it, may be opened by striking the de- 15 vice from the exterior of the door with the wheel or fender of an automobile.

A further object is the provision of man- 20 ually operable means whereby the door may be opened from the inner side and, if de- sired, may be held in unfastened position.

Other objects and advantages of the in- 25 vention will appear from the following de- scription taken in conjunction with the ac- companying drawings which form a part of this specification and illustrate the preferred embodiment of the invention.

In the drawings:

Figure 1 is a front or exterior elevation 30 of a pair of doors carrying my invention, and shows also a fragment of the garage wall in which the doors are hung:

Fig. 2 is a rear or interior elevation of the parts shown in Fig. 1:

Fig. 3 is a section taken approximately 35 on line 3—3 of Fig. 1; and

Fig. 4 is a perspective view of a shank guide which I employ.

In a garage wall 10 having a double door aperture 11, are hung a pair of inwardly 40 opening doors 12 and 13 mounted on spring hinges 14 so that they will open automatically when released from their fastenings. A vertical slot 15 is cut in the door 12 and a leaf spring 16 is positioned in the slot 45 and fastened by its lower end to the inner face of the door. This spring is bowed outwardly through the slot, preferably so far that it protrudes considerably from the outer surface of the door, and it bends in- 50 wardly so as to reenter the slot near the top thereof. This spring 16 is extremely stiff so that the unaided efforts of the ordinary person cannot bend it, but it may readily be bent by a blow from the fender or wheel 55 of an automobile. By the use of such a

strong spring I provide a door fastening device not easily released by unauthorized persons without the use of an automobile or other movable body of large inertia.

Somewhat above the top of slot 15 the 60 doors are each fitted with horizontally alined bar receiving brackets 17 and 18 which are open at the top in a well-known manner and receive a fastening bar 19 to se- 65 cure the doors in closed position. By ele- 70 vating the bar into the dotted line position of Fig. 2 the doors are released to the ac- 75 tion of their spring hinges. At one end the bar 19 is bent outwardly of the door 13 through a small vertical slot provided, and this bent end is pierced to stand opposite the hole pierced in a stud 21 riveted to the outer face of door 13. A padlock 22 may be passed through these two elements to lock the doors closed.

Just above the upper end of slot 15 a shank guide 23 is fixed to the inner surface of door 12, this guide appearing in perspec- 80 tive in Fig. 4. Depending from the bar 19 is a shank 24 that stands just above the slot 85 15 and is riveted at its lower end to the upper end of spring 16. This shank passes through the guide 23 which turns the in- 90 ward movement of the upper end of the spring into vertical reciprocation of the shank and bar.

The spring 16 normally holds bar 19 in its lower position, fastening the doors closed, but the bar may be raised and the doors released by the impingement of an automo- 95 bile wheel 25 or fender 26 against the outer side of the spring. To facilitate striking the spring with the wheel of a vehicle I rivet a bumper 27 to the spring 16, placing it horizontally.

Extra fastening means may be employed in the form of two ordinary, vertically re- 100 ciprocable bolts 28 and 29 respectively positioned to enter bolt holes provided in the lintel and threshold of the opening 11. These bolts are mounted in keepers 31 and 32 respectively and at their inner ends are pivoted to a lever 33 which oscillates about a stub shaft 34. A bolt arm 35 fixed to bolt 29 rides in a horizontal slot 36 formed in 105 bar 19 and reciprocates the bolts with the bar to draw them.

An angle plate 37, positioned near the bot- 110 tom of slot 15 and protruding back of the slot, forms the fulcrum for a hand lever 38

which, by means of a link 39, is connected to the inner side of spring 16 near its center as at 41. As the link is pivoted to the lever near the fulcrum a pull on the lever 5 will enable the ordinary person to bend the spring inwardly and so release the closed doors from within the garage. The lever 38 carries a rack 42 adapted to be engaged by a pawl 43 pivoted to the door 12. By 10 placing the pawl in one of the lower notches of the rack the bar 19 can be held out of the brackets 17 and 18.

My invention is of use, for instance, in connection with the doors of a public garage. During a storm it is necessary to keep the doors shut, yet those wishing to store their cars or obtain repairs can open the doors and drive into the garage without a moment's waiting or dismounting into the 20 storm. This is accomplished by allowing the automobile to drift against the bumper 27; the inertia of the heavy car readily bending the spring inward sufficiently to raise bar 19 from the brackets 17 and 18 25 and simultaneously withdraw bolts 28 and 29. Obviously it may be adapted to a single door instead of double doors.

While I have illustrated and described the preferred embodiment of my invention, 30 it is obvious that one skilled in the art may make modifications thereof without departing from the spirit of the invention. I wish, therefore, not to be restricted to the precise embodiment shown except in so 35 far as the same is limited in the appended claims.

I claim:

1. The combination with a pair of doors mounted to swing inwardly, of a stiff leaf 40 spring bowed outwardly of one door and fixed thereto by its lower end, horizontally alined brackets on the doors above the spring, a reciprocable bar movable into the brackets to fasten the doors in closed position, a depending shank on the bar secured at its lower end to the free end of the spring, and a guide for the shank fixed to 45 said one door and positioned to limit the shank to vertical movement.
2. The combination with a pair of doors 50 mounted to swing inwardly, of a stiff leaf spring bowed outwardly of one door and fixed thereto by its lower end, horizontally alined brackets on the doors above the 55 spring, a reciprocable bar movable into the brackets to fasten the doors in closed position, a depending shank on the bar secured at its lower end to the free end of the spring, a guide for the shank fixed to said one door 60 and positioned to limit the shank to vertical movement, and latch mechanism including a pair of vertically reciprocable bolts one of

which is connected to said bar for movement therewith.

3. The combination with a pair of doors 65 mounted to swing inwardly, of a stiff leaf spring bowed outwardly of one door and fixed thereto by its lower end, horizontally alined brackets on the doors above the spring, a reciprocable bar movable into the 70 brackets to fasten the doors in closed position, a depending shank on the bar secured at its lower end to the free end of the spring, a guide for the shank fixed to said one door and positioned to limit the shank to vertical movement, and a horizontal bumper fixed to the spring outwardly of said one door. 75

4. The combination with a door, and devices for fastening the same in closed position including a member movable to fasten 80 or release the door, of vehicle operated means exposed outwardly of the door for moving said member to releasing position and normally spring pressed to hold the member in door-fastening position, and a lever manually operable from the inner side of the door for moving the member to releasing position. 85

5. The combination with a door, and devices for fastening the same in closed position including a member movable to fasten 90 or release the door, of vehicle operated means exposed outwardly of the door for moving said member to releasing position and normally spring pressed to hold the member in door-fastening position, a lever manually operable from the inner side of the door for moving the member to releasing position, a 95 rack on the lever, and a pawl pivoted to the door and engaging the rack to hold the lever 100 in door-releasing position.

6. The combination with a door having a slot, of door fastening elements carried thereby, a stiff leaf spring bowed outwardly of the door, fixed thereto at its lower end 105 and operatively connected at its free end to said elements, a lever fulcrumed near said spring, and a link connecting the center of the spring with a point on the lever near said fulcrum. 110

7. The combination with a door having a slot, of door fastening elements carried thereby, a stiff leaf spring bowed outwardly of the door, fixed thereto at its lower end and operatively connected at its free end to 115 said elements, a lever fulcrumed near said spring, a link connecting the center of the spring with a point on the lever near said fulcrum, a rack on the lever, and a pawl pivoted on the door and engaging the rack 120 to maintain tension on said spring.

In testimony whereof I affix my signature.

CHARLES M. OHLSEN.
